James J. Davelin

United States Patent Office.

JAMES J. DAVELIN, OF PHILADELPHIA, PENNSYLVANIA.

Letters Patent No. 63,023, dated March 19, 1867; antedated March 5, 1867.

IMPROVEMENT IN CHURNS.

The Schedule referred to in these Letters Patent and making part of the same.

TO ALL WHOM IT MAY CONCERN:

Be it known that I, JAMES J. DAVELIN, of the city of Philadelphia, in the county of Philadelphia, in the State of Pennsylvania, have invented a new and improved mode of constructing "Churns;" and I do hereby declare that the following is a full and exact description thereof, reference being had to the accompanying drawings, making a part of this specification, in which

Figure 1 is a perspective view of my churn.

Figure 2, a longitudinal sectional elevation of the same.

Figure 3, a cross-sectional elevation of the same.

Figure 4, a section on a larger scale, showing the iron fixtures and fastenings, as hereafter described—

Similar letters referring to similar parts all throughout the following description.

The nature of my invention consists in constructing my churn in a barrel-shaped form, and providing it with two dashers of a peculiar form, which are intended to revolve on fixed points, but in contrary directions, thus causing the cream to be beaten more thoroughly, and preventing its swelling during the operation.

To enable others skilled in the art to make and use my invention, I will proceed to describe its construction and operation.

B B is the body of the churn, made and hooped as any ordinary light cask, out of any suitable material, wood or metal.

N M N M and P O P O are two frames, made so as to fit inside the barrel or body of the churn, and so that the smaller will fit loosely inside the larger, as shown in fig. 2.

A shaft, A, is made to run through the centre of one end of churn, and is fastened on piece N of frame or dasher N M N M, said shaft is provided with a conical centre hole, x, on the inside end, and with a crank-handle, K, on the outside.

The opposite piece of the same frame N M N M is provided with a hollow washer, D D, fastened on the centre of said piece, and through which runs a shaft, A', similar to the one, A, above described, and which fastens, as shown in y y, on centre of piece P of small frame or dasher P O P O, shaft A' passing through the end of churn, and provided on its (shaft's) outside end with a crank-handle, K'.

On centre of opposite piece P of smaller frame P O P O is fastened pivot C, resting and fitting easy in conical hole x.

Holes II' II', in suitable numbers, and of suitable sizes, are made into curved pieces M and O of dashers.

Lid L permits the introduction of the cream and extraction of the butter, and these complete the invention.

Now, the cream having been introduced into churn through lid L, if two children, or any couple of hands, revolve rapidly and in contrary directions, as shown in fig. 3 by arrows a a a and b b b, the dashers N M N M and P O P O, the cream will be so thoroughly and unceasingly moved and in rapid motion that the globules containing the butter will soon be crushed open, coagulated together, and butter be obtained in a short time, with scarcely any labor.

Having thus described my invention, what I claim as my invention, and desire to secure by Letters Patent of the United States, is—

The combination of dashers N M and P O, constructed and held together by fastenings A, W, C, and D, with churn B, the whole combined and acting in the manner and for the purpose above described and shown.

JAMES J. DAVELIN.
